UNITED STATES PATENT OFFICE.

HARRY STILLSON HART, OF CHICAGO, ILLINOIS, ASSIGNOR TO NATIONAL COAL DUMP CAR COMPANY, OF RAPID CITY, SOUTH DAKOTA, A CORPORATION OF SOUTH DAKOTA.

DUMP-CAR.

SPECIFICATION forming part of Letters Patent No. 719,795, dated February 3, 1903.

Application filed February 10, 1902. Serial No. 93,389. (No model.)

To all whom it may concern:

Be it known that I, HARRY STILLSON HART, a citizen of the United States, residing at Chicago, in the county of Cook and State of Illinois, have invented certain new and useful Improvements in Dump-Cars, of which the following is a specification.

This invention relates to that class of cars known as "dump-cars"—that is, gondola cars—provided with flat bottoms and side and end boards and a dumping-hopper bottom, all of which will more fully hereinafter appear.

The principal object of the invention is to provide a simple, economical, and efficient dump-car of such construction and arrangement that it may have all the advantages of a flat-bottom gondola and an A-shaped dumping-car.

A further object of the invention is to provide a car of the class described with means for protecting the chain or other device by which the bottom of the car is operated.

Further objects of the invention will appear from an examination of the drawings and the following description and claims.

The invention consists, primarily, in a dump-car in which there are combined a supporting-frame portion provided with side and end boards, an A-shaped central portion arranged in two planes—high and low—and provided with foldable doors pivotally connected thereto and extending out therefrom, and means for operating these doors by which they may be made to form flat-bottom portions or inclined dumping-boards, respectively.

The invention consists, further and finally, in the features, combinations, and details of construction hereinafter described and claimed.

In the accompanying drawings, Figure 1 is a plan view of one end of a car constructed in accordance with these improvements, showing the foldable portions on one side arranged in a horizontal plane and those on the other side laid in an inclined plane looking at it from above; Fig. 2, a longitudinal sectional view of the same, taken on line 2 of Fig. 1 looking in the direction of the arrow; Fig. 3, a cross-sectional view taken on line 3 of Fig. 1 looking in the direction of the arrow; Fig.

4, a cross-sectional view taken on line 4 of Fig. 1 looking in the direction of the arrow; Fig. 5, an enlarged perspective sectional detail showing a portion of the side boards and other parts hereinafter referred to; Fig. 6, an enlarged sectional detail taken on line 6 of Fig. 1; Fig. 7, perspective details of the hinges by which the foldable parts are swung into and out of position; Fig. 8, a cross-sectional view similar to that shown in Fig. 3, with a modified form of housing to protect the rock-shaft; Fig. 9, a cross-sectional view similar to that shown in Fig. 4, illustrating a modified form of housing; Fig. 10, a plan detail of one side of the car as it appears when constructed similar to that shown in Figs. 8 and 9; Fig. 11, a sectional elevation of a portion of the mechanism, showing the inside of one of the side boards, taken on line 11 of Fig. 8 looking in the direction of the arrow; and Fig. 12, a side elevation of the supporting-framework, side boards, and rock-shaft of Fig. 11 looking at the parts from the outside.

In the art to which this invention relates it is well known that it is desirable to provide a dumping-car which will discharge all of the material through the bottom and down inclined bottom portions both from above the trucks and from the part between the trucks. It is also desirable to so construct and arrange the parts as to provide large discharge-openings and keep the center of gravity of the car as close to the track as possible. It is further desirable to protect the locking and operating mechanisms as much as possible from the destructive action of the load during the transportation of the car. To accomplish these ends, this invention is primarily designed, all of which will be more fully hereinafter set forth.

In constructing a car in accordance with these improvements I provide supporting-framework formed of the side sills *a*, end sills *b*, cross-sills *c*, and intermediate and center sills *d* and *e*, upon and to which are secured the side boards *f* and the end boards *g*.

To provide a bottom for the car which will carry almost any desirable kind of freight and permit of the discharge of certain kinds, such as ballast or coal, by means of such bottom

and in an automatic manner both above and between the trucks and to the outside of the usual car-tracks, I provide a bottom portion, formed in three central apex or A-shaped sections and which occupy what I prefer to term "high" and "low" levels—that is, the apexes *h* at the ends of the car. Those arranged over and above the trucks are at high levels, while the apex *i*, arranged between the trucks, is 10 at a lower level, and all are substantially in line with the longitudinal center of the car.

Pivotedly secured to the framework of the car, substantially at what might be termed the "floor-level" thereof and so as to form 15 practically continuations of the A-shaped apex portions, are a plurality of doors *j* and *k* at each side of the car, which doors, as above suggested, are pivoted, so that their free ends extend outwardly and when dropped into the 20 position shown in Figs. 3, 4, 8, and 9 form substantial continuations of the central apex portions and inclined dumping-boards. By this arrangement it will be seen that material 25 the entire length of the car may be discharged to a point or points outside of the supporting-tracks and that the center of gravity is maintained at as low a point as possible. These doors can also be folded or swung upwardly to occupy a horizontal plane and flat bottom 30 portion of the car, thereby permitting the transportation of any kind of freight desired.

To open and close the doors, rotatable shafts *l* are provided, one arranged at each side of the car and supported in suitable bearings 35 just inside of the side boards thereof. Connecting-chains *m* are provided and secured to such shafts and to the ends of the swinging doors, so that as such shafts are rotated the chains are wound around them and the 40 doors raised thereby. When such shafts are rotated in an opposite manner, the doors are permitted to drop and open by the weight of the load contained within the car or gravity. As these shafts and chains are arranged on 45 the inside of the car, it is desirable that they should be protected from the injurious action of the freight, particularly ballast and coal, which would otherwise tend to obstruct the free operation thereof, as well as subject 50 them to an injurious and unnecessary wearing action. To prevent this, housings *n* are provided, preferably formed, as shown in Fig. 5, of a metallic frame portion, which also provides bearings for the rotatable shafts and a 55 hood for protecting the chain from the wearing and other actions of the load.

In Figs. 8, 9, 10, 11, and 12 I have shown these housings or hoods as formed of boards and running the entire length of the car between the side stakes or posts *q*. Either of 60 these forms of protecting-hoods may be used, according to the economy of manufacture or desire of the user.

It is well known that usually the side sills 65 of cars are arranged below the floor-level, and if such were the arrangement in this construction the size of the discharge-opening

between such sills and the free end of the door would be limited and more or less choking during discharge of load would occur. 70 In order, therefore, to provide as large a discharge-opening as possible without interfering with the strength or efficiency of the cars, I provide the side sills *a*, above referred to, and arrange them above the floor-level and 75 on the cross-sills or timbers *c*, as shown in the drawings, which provides for maximum discharge-openings.

I claim—

1. In a dump-car of the class described, the 80 combination of a supporting-frame provided with side and end boards, a dumping-bottom portion formed of central A-shaped apex portions arranged in two horizontal planes, and swinging doors extending outwardly therefrom and forming a flat bottom of the car in one position and inclined dumping-boards in a second position, substantially as described.

2. In a dump-car of the class described, the 85 combination of a supporting-frame portion provided with side and end boards, a dumping-bottom portion formed of central A-shaped apex portions arranged in two horizontal planes extending substantially the entire length of the car, and swinging boards pivotally secured thereto at the ordinary floor-level and extending outwardly therefrom to 90 form flat bottom portions in one position and inclined dumping-boards in a second position, substantially as described.

3. In a dump-car of the class described, the 95 combination of a supporting-frame portion provided with side and end boards, a dumping portion formed of central A-shaped apex portions arranged in different horizontal 105 planes, the end sections of which are arranged in a high plane above and over the trucks of the car and the central section in a lower plane between the trucks, and swinging boards pivotally secured thereto and extending out 110 therefrom and forming flat bottom portions in one position and inclined dumping-boards in a second position, substantially as described.

4. In a dump-car of the class described, the 115 combination of a supporting-frame portion provided with side and end boards, a dumping bottom portion formed of central A-shaped apex portions arranged in different horizontal planes, the end sections of which are arranged in a high plane above the trucks of the 120 car and the central section in a lower plane between the trucks, swinging boards pivotally secured thereto and extending out therefrom and forming flat bottom portions in one position and inclined dumping-boards in a second 125 position, a rotatable shaft arranged at each side of the car and inside of the side boards thereof, and a plurality of chains connecting the free ends of the dumping-boards with the rock-shafts, substantially as described.

5. In a dump-car of the class described, the 130 combination of a supporting-frame portion provided with side and end boards, a dumping bottom portion having central A-shaped

apex portions extending horizontally over the trucks to the extreme ends of the car and swinging boards pivotally secured thereto and extending out therefrom throughout the 5 entire length of the car and over the trucks to the extreme ends of the car-frame so as to form flat bottom portions in one position and inclined dumping-boards in another position, a rotatable or rock shaft arranged at each 10 side of the car inside the side boards thereof and above the floor-level, a plurality of chains secured to the free ends of the dumping-boards and to the rotatable shafts, and hood mechanism arranged inside of the side boards 15 surrounding the rotatable shaft and over its connection with the chain to protect the same, substantially as described.

6. In a dump-car of the class described, the combination of a supporting-frame portion 20 having side sills arranged above the ordinary floor-level and provided with side and end boards, a dumping bottom portion formed of central A-shaped apex portions arranged centrally of the car and extending horizontally 25 from end to end thereof over the trucks and swinging boards pivotally secured thereto and extending out therefrom throughout the entire length of the car and over the trucks,

and means for raising and lowering the swinging boards into a horizontal plane to form flat 30 bottom portions in one position and into an inclined plane to form dumping-boards in another position, substantially as described.

7. In a dump-car of the class described, the combination of a supporting-frame having its 35 side sills arranged above the ordinary floor-level and provided with side and end boards, a dumping bottom portion formed of central A-shaped apex sections arranged in different horizontal planes, swinging boards pivotally 40 secured thereto and extending out therefrom to form flat bottom portions in one position and inclined dumping-boards in another position, a rotatable shaft arranged on the inner side of each of the side boards, a plurality of 45 chains connecting the free ends of the dumping-boards to its respective rotatable shaft, and hood mechanism arranged inside of the side boards surrounding the rotatable shaft at its point of connection with the connecting- 50 chains to protect the same, substantially as described.
